UNITED STATES PATENT OFFICE.

JOSEF GRANZ, OF PLAUEN, GERMANY, ASSIGNOR TO VOGTLÄNDISCHE MASCHINEN-FABRIK, OF PLAUEN, GERMANY.

SHUTTLE.

1,182,366.

Specification of Letters Patent.

Patented May 9, 1916.

Application filed August 28, 1914. Serial No. 859,078.

To all whom it may concern:

Be it known that I, JOSEF GRANZ, a subject of the German Emperor, residing at Plauen, in Vogtland, in the Kingdom of 5 Saxony, Germany, have invented certain new and useful Improvements in Shuttles, of which the following is a specification.

The present invention relates to shuttles for embroidering machines and consists in 10 the novel construction of an embroidery shuttle. As hitherto constructed the back of the shuttle rises from its pointed end more or less gradually to a maximum height which is located behind the middle and near 15 the rear end of the shuttle and thence curves down abruptly. When numerous shuttles of such structure pass through the needle loops a sudden vigorous jerk is produced at the last moment. This is due to the fact 20 that when the outrunning shuttle has almost advanced to the end of its stroke, the needle loop engaging around it has not yet reached the highest point but still travels on the rising portion of the shuttle. Only just at the 25 very end of the stroke the loop arrives at the highest point and drops down very suddenly. By reason of this fact the needle necessarily must remain a comparatively longer period in its deepest position, and 30 only an extremely short time is left for its return movement, in consequence of which the machine is vigorously shaken. Frequently, also owing to the loop being 35 strongly tensioned before it drops off the shuttle breakage of thread is occasioned.

The object of my invention is to obviate the grave drawbacks above referred to.

In the accompanying drawing which forms part of this specification and in which

similar reference characters denote corresponding parts the figure illustrates a side view of my new shuttle.

The shuttle *a* is so constructed that the back thereof rises at an acute angle to a point *a'* which is located on a line *y* and 40 which is in advance of the middle of the shuttle indicated by the dotted line *x*, then from that point *a'* tapers gradually toward the rear and finally drops in an abrupt curve 45 to the bottom of the shuttle. Consequently 50 the needle thread loop *b* will by itself slide off the back of the shuttle without danger of breaking. Furthermore, another more important advantage of the new structure is 55 that the return movement of the needle may be much smoother because the needle *c* may begin its retreat at the moment the loop reaches its highest point at *a'* of the shuttle. It is of course understood that the taper of 60 the back behind the highest point *a'* may be 65 made more gradual than shown.

What I claim and desire to secure by Letters Patent is:

As an article of manufacture, an embroidery machine shuttle, of which the back rises 65 from the pointed end at an acute angle to a point located in advance of the middle vertical line of the shuttle, then from that point tapers gradually down toward the rear and is curved abruptly toward the bottom of the 70 shuttle, substantially as and for the purpose set forth.

In testimony whereof I affix my signature in presence of two witnesses.

JOSEF GRANZ.
